UNITED STATES PATENT OFFICE.

HAROLD DE OLANETA, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

DRY CELL.

Original application filed April 1, 1920, Serial No. 370,610. Divided and this application filed May 7, 1920. Serial No. 379,515.

To all whom it may concern:

Be it known that I, HAROLD DE OLANETA, a citizen of the United States, residing in New Haven, New Haven County, Connecticut, have invented certain new and useful Improvements in Dry Cells, of which the following is a full, clear, and exact description.

This invention relates to dry cells, and 10 is particularly applicable to those of the pocket or miniature type, such as commonly employed in connection with flash-lights, although the invention is not necessarily limited in this respect.

15 This application is a division of my application Serial No. 370,610, filed April 1, 1920, and pertains more especially to the arrangement of parts within the lower end of the zinc cup.

20 One of the primary objects of the invention is to furnish an improved form of element for centering the cartridge of depolarizing material within the lower end of the zinc cup.

25 To these and other ends, the invention consists in the novel features and combinations of parts hereinafter described and claimed.

In the accompanying drawings:

30 Fig. 1 is a vertical central section of a dry cell embodying my improvements;

Fig. 2 is a similar view, with the bottom centering cup shown in elevation;

35 Fig. 3 is a top plan view of the centering cup;

Fig. 4 is a bottom view of the centering cup;

Fig. 5 shows the blank from which the centering cup is made.

40 In the cell shown in the drawing, the zinc cup 10 constituting one electrode contains a carbon pencil 11, which serves as the other electrode. The carbon electrode carries a depolarizing cartridge 12, consisting 45 of suitable powdery or granular depolarizing material tamped about the carbon in order to form a block or cartridge adhering to the same. The cartridge is preferably enclosed in a porous envelope, such as a bag 13 of cheese-cloth or the like. Between the side surface of the cartridge and the inner surface of the side wall of the 50 zinc cup is a suitable electrolytic paste 14.

In the bottom of the zinc cup is a centering disk 15, which will be referred to in detail hereinafter. At the top of the zinc cup, the latter is closed in an appropriate manner, as by means of a plug 16 of insulating fibre or other suitable material, the particular nature and construction of which is not material so far as the present invention is concerned, the same being claimed in my application Serial No. 321,068. On the upper end of the carbon electrode 11 is the usual brass contact cap 17.

The paste 14 may contain, for example, suitable proportions of cereal, such as wheat flour; chlorid solution, such as zinc chlorid for example; and an amalgamating substance, of which mercuric chlorid is an example. The activating electrolyte usually consists of a solution of ammonium chlorid, which may be placed initially in the depolarizing cartridge, or in the paste, or in both, as may be desired.

The bottom centering disk 15 is preferably made of paper, impregnated with paraffin. The upper edge of this disk, which is cupped and adapted to fit about the lower end of the cartridge, is provided with cut-out portions, indentations or scallops 18, the purpose of which is to increase the amount of paste and thereby the amount of electrolyte carried thereby which may act on the zinc cup and on the cartridge at the lower portion of the cell. In other words, it is desirable to provide a maximum area of contact between the paste and the cartridge on the one hand, and between the paste and the zinc on the other hand, without interfering in any way with the effective action of the cupped disk in centering the cartridge with substantial accuracy in the bottom of the zinc cup. The centering function of the paper cup is important, as the zinc will be attacked unevenly if the layer of paste in contact with the same is not substantially uniform throughout the circumference of the cell. The paper cup shown in the drawings meets these conditions admirably, because the scallops or cut-out portions 18 permit considerable action of the electrolyte on the cartridge and zinc cup at the lowermost part of the cell, while the upward projections on the flange of the paper cup intermediate these scallops or

indentations secure a very efficient centering of the cartridge.

The scalloped centering cup may be readily manufactured. It may be formed, for example, by cupping a disk-like paper blank 15^a, shown in detail in Fig. 5. This blank is cupped in a convenient manner, and in the cupping operation suitable projections on the cupping tool are brought down to 10 engage the upper edge of the cup and thereby form the depressions or scallops 18. In the preferred practice, the depressions or scallops are formed by bending or folding the paper at a number of equally distant 15 points, the depressions or scallops being produced in effect by a crushing of the side wall of the cup at those points.

I do not claim herein the method of making the scalloped bottom centering cup for 20 the depolarizing cartridge, as the same is claimed in my copending application, Serial No. 392,287.

What I claim is:

1. In a dry cell, a container, a depolarizing cartridge therein, and a bottom centering cup for the cartridge, having a continuous stiffened side wall with scallops formed therein.
2. In a dry cell, a container, a cartridge 30 therein, and a cup for centering the cartridge in the bottom of the container, said cup having a continuous stiffened turned peripheral flange with centering projections on its edge.
3. A shallow centering cup for a dry cell 35 cartridge having a bottom, an unyielding peripheral wall upstanding therefrom, and

a plurality of centering projections formed on the wall.

4. A shallow paper centering cup for dry 40 cell cartridges having a bottom, and an unyielding peripheral wall upstanding therefrom, said wall being crushed or folded to provide a plurality of centering projections. 45

5. In a dry cell, such as described, a containing cup, a cartridge therein, having an imbedded electrode, a centering member for the cartridge in the bottom of the cup, said centering member of cupped form and having a continuous side wall with scallops or indentations in the upper edge thereof, a paste interposed between the cartridge and the side wall of the cup and substantially filling such scallops or indentations, and 55 a closure for the top of the cup.

6. In a dry cell, a container, a cartridge therein, and a centering member for the cartridge in the bottom of the container, said centering member consisting of a disk of 60 flexible fibrous material having a continuous side wall generally perpendicular to the disk.

7. In a dry cell, a container, a cartridge therein, and a centering member for the 65 cartridge in the bottom of the container, said centering member consisting of a disk of flexible fibrous material having a continuous side wall, with scallops or indentations in its upper edge. 70

In witness whereof, I have hereunto set my hand on the 5th day of May, 1920.

HAROLD DE OLANETA.
